GARTER GRIP

Fred S. Clark, New York, N. Y.

Application March 31, 1950, Serial No. 8,887

Term of patent 3½ years

(Cl. D17—8)

To all whom it may concern:

Be it known that I, Fred S. Clark, a citizen of the United States of America, residing in New York city, county of New York, and State of New York, have invented a new, original, and ornamental Design for a Garter Grip, of which the following is a specification, reference being had to the accompanying drawing, forming part thereof, wherein,

I claim:

The ornamental design for a garter grip, substantially as shown.

FRED S. CLARK.
